UNITED STATES PATENT OFFICE.

DAVID M. LEACH AND WINFIELD S. SLINKER, OF SULPHUR WELL, KY.

WHEAT-CLEANING MACHINE.

SPECIFICATION forming part of Letters Patent No. 242,339, dated May 31, 1881.

Application filed October 23, 1880. (Model.)

To all whom it may concern:

Be it known that we, D. M. LEACH and W. S. SLINKER, both of Sulphur Well, in the county of Metcalf and State of Kentucky, have invented a new and valuable Improvement in Wheat-Cleaners; and we do hereby declare that the following is a full, clear, and exact description of the construction and operation of the same, reference being had to the annexed drawings, making a part of this specification, and to the letters and figures of reference marked thereon.

Figure 1 of the drawings is a representation of a side view of a machine in which this invention is incorporated. Fig. 2 is a vertical longitudinal section, and Fig. 3 is a vertical transverse section of the same.

This invention relates to devices for cleaning wheat and other grain.

It consists in the construction hereinafter specified.

In the annexed drawings, A is a box or closed frame containing my devices. The top is open, and across the same is a slanting reciprocating riddle, B, above which is the hopper C. At its upper end this riddle is hinged to the frame by pins passing through loops on the frame. Extending from this end of the riddle, across the same and to its lower end, is a pliant rod, D, fastened at the upper end of the riddle, and at its other end to a crank on shaft E. By making this rod D pliant, while the riddle is shaken the pliancy of the rod gives to the riddle a quivering motion, which keeps the imposed matter agitated and causes the riddle to act like a sifter. At its lower end the riddle B has a pin, b, which engages with a spring, F, fastened to the frame A. The shaft E turns in bearings e e', and has a pulley, e'.

Below riddle D, and slanting in the opposite direction, is an apron, H. The lower edge, h, of this apron projects under the inner partition, i, of a wind-chute, I, the side edge, h, being on a slant with the lower edge of said partition, so as to make the edges meet at one end and be apart at the other, whereby a wedge-shaped opening, h', into said wind-chute I is formed. This chute I extends up beyond the opening e' to the top of the frame A, and opens into an outlet-chute, K. The chute I extends downward and leads into a chamber, L. The

bottom of this chamber has a concave, M, with perforations m. Leading from the end of wind-chute I, immediately below the larger part of opening h', and extending obliquely across a portion of the face of perforated concave M, is a spout, N. By making the opening wedge shape and putting spout N just under the larger part of this opening the sifted matter is conducted right over the opening into this spout and falls at the right place for entering this spout. Beneath concave M is a V-shaped trough, P, having opening p at the bottom. The concave M has the usual pitch, and at the end m' thereof is an inclined hopper, R, leading through an opening, r, into a spout, S, leading in opposite directions, s s', said spout being held up by a latch, s'.

Projecting longitudinally through chamber L is a shaft, T, journaled in bearings at each end and having rigidly affixed to it the beaters t t and fan V, the beaters being above the concave M and the fan above the inclined hopper R.

To one end of shaft T is a driving pulley or crank and at the other a pulley engaging by a belt the pulley e' upon shaft E. In the frame are suitable openings to admit air, and others for viewing the operation of the device.

Grain is poured into the hopper C, which guides it down to the riddle B. Falling upon this, it is agitated by the reciprocating of the same, and the grain, fine dirt, smut, and other small particles fall through the openings in the riddle, and large particles slide off and drop to the ground. Passing from the riddle through opening h' into wind-spout I, the grain and small particles come in contact with wind driven up by fan V, whereby the dust and small particles of smut unbroken are driven up to the top and out at chute K. The grain and other and heavier particles of dirt slide down chute I and through spout N to the upper part of concave M. Sliding down this, the grain and dirt are operated upon by the beaters, which break the dirt up, and as they fall through inclined hopper R the fan drives the dirt up through end s of spout S, the wheat falling down through end s'. The shape given the opening from the grain-board H to the chute I and the construction and location of the fan below cause the greatest volume of grain to fall at the point of the strongest blast, whereby

it is better winnowed and more thoroughly cleansed.

What we claim is—

The combination, with the fan located at 5 one end of the machine on the beater-shaft, of the upright blast-chute formed with a horizontal wedge-shaped opening in one wall thereof, and the obliquely-inclined grain-board H discharging into said chute, whereby the greatest volume of the grain falling through the

chute is brought into contact with the strongest blast.

In testimony that we claim the above we have hereunto subscribed our names in the presence of two witnesses.

DAVID McELWEE LEACH.
WINFIELD SCOTT SLINKER.
